(57) **CLAIM**

(22) Filed: **May 29, 2009**

We claim the ornamental design for a container with scrub pad, as shown and described.

(51) **LOC (9) Cl.** **09-01**

DESCRIPTION

(52) **U.S. Cl.** **D9/719**

FIG. 1 is a perspective view of a portion of a container with scrub pad showing our new design;

(58) **Field of Classification Search** D9/444-447,

FIG. 2 is a front view thereof;

D9/449, 516, 521, 522, 530, 535, 537-543,

FIG. 3 is a rear view thereof;

D9/549, 558, 574, 575, 682, 686, 689, 691,

FIG. 4 is a right side view thereof;

D9/693, 715, 718-720, 722; 220/660-662,

FIG. 5 is a left side view thereof;

220/669, 675; 215/382-384, 396, 398; D8/71,

FIG. 6 is a top view thereof; and,

D8/349, 354, 367, 373, 382

FIG. 7 is a bottom view thereof.

See application file for complete search history.

The broken lines shown throughout these figures show unclaimed subject matter only and form no part of the claimed design.
